UNITED STATES PATENT OFFICE.

RICHARD D. GALLAGHER, OF CHICAGO, ILLINOIS, ASSIGNOR TO ROCS FOUNDRIES, INC., OF CHICAGO, ILLINOIS, A CORPORATION OF ILLINOIS.

BUMPING POST.

Application filed March 2, 1922. Serial No. 540,403.

To all whom it may concern:

Be it known that I, RICHARD D. GALLAGHER, a citizen of the United States, residing at Chicago, in the county of Cook and State of Illinois, have invented certain new and useful Improvements in Bumping Posts, of which the following is a specification.

My invention relates to railway bumping posts, and particularly to a form of construction thereof whereby the shocks of bumping may be transferred directly to the supports which maintain the bumping block in position without permitting any strain on the bolts securing the parts together.

15 An object of my invention is to provide a bumping post having a bumping block, formed preferably of cast metal, and in recessed engagement with its supports.

Another object of the invention is to provide a bumping post having the several parts thereof formed of metal with the supports made of railroad rails such as T-rails and bent into substantially U shape, and with the bumping block made of cast metal and provided with recesses for receiving portions 25 of the supports for maintaining the block in proper position at all times.

A further object is to improve bumping post construction for generally successful 30 commercial use, and to provide a post which may be readily manufactured, shipped and erected.

The above recited and other objects of the invention will be apparent from the following description and drawings and will be 35 particularly pointed out in the appended claims.

In the drawings:

Figure 1 is a side elevational view of the 40 preferred form of my invention.

Figure 2 is a top plan view of Figure 1, and

Figure 3 is a view, partially in section, taken on line 3—3 of Figure 2.

45 To track rails 5 and 6 are secured the supports of the bumper of my invention. The bumping post comprises a bumping block 7 of cast metal and substantially box like in form. The block has a flat end surface 8 against which the car couplers strike as is the usual practice. The supports of my invention are two in number, each formed of preferably T-rails and each being continuous from end to end. Referring to the drawings, the supports as may be observed, are

each bent into substantially U shape and inverted as to position in both plan and elevation. The central portions of the bend in elevation are curved as may be observed in Figure 1; while in plan, the central portions 60 are straight, as will be seen in Figure 2. The ends of each of the rails forming the supports are straight as at 9 and are provided with bolt holes 10 through which bolts 11 may be passed for securing the bumping 65 post to the track rails 5 and 6. In plan each rail support is bent inwardly forming inclined portions 12 and with the central portions straight as at 13. Each support is like the other, and both are formed in the same 70 manner and are interchangeable. In elevation the central part 13 which in plan is shown as straight is curved as at 14 in Figure 1, and is provided with bolt holes 15. The bumping block 7 is preferably hollow for 75 the purpose of economy in manufacture, suitably reinforced by strengthening ribs such as 16 and has formed in its sides recesses or grooves 17 which are curved and shaped exactly to correspond to the central portions 80 of the supporting members which in the present instance, are T-rails; that is, the cross section of the recess in the block is that of a T-rail as may be observed in Figure 3. Bolts 18 are passed through the apertures 15 85 in the supports and registering apertures in the block 7 for fastening the various parts together.

The construction of the supports and the recessed engagement of the same with the 90 bumping block is of such a nature and kind that when a bumping shock is imparted to the block, the shock will be imparted to the supports through the recessed engagement of the same with the block, thus relieving the 95 bolts 18 from any strains whatsoever. The curvature in elevation of the recesses in the side of the block is non-circular, for the purpose of preventing the block sliding backwards under bumping impact. Non-slip- 100 page of the block is also maintained by providing an irregular cross-sectional engagement of the supports with the block. It will be observed that the line of impact against the face 8 of the block is below the top of the 105 central curve 14 of the side supports, which is another reason why the block would not slide over backwards under impact.

In order to prevent shearing of the bolts 11 which fasten the supports to the track 110

rails 5 and 6, and in order to maintain track alignment, I provide brace bolts 19 arranged as shown in Figure 2, that is, with one at each end of the bumping post which bolts have shoulders 20 to bear against the inner side of the webs of the supports so that when bumping shocks are imparted to the block the brace bolts 19 will oppose contraction of the supports where the same are fastened to the track rail, thus maintaining track alignment and preventing breakage of the track bolts.

It will be observed that a bumping post constructed in accordance with my invention may be easily manufactured and shipped in a knocked-down condition and readily assembled wherever desirable at minimum cost. The only work necessary to be done is to drill track rails 5 and 6 for the reception of the bolts 11 which fasten the bumping post supports to the track rails; furthermore, by making each of the supports of a single continuous rail added strength is secured in the structure and separation of parts is prevented. By reason of the recessed engagement between the block and the supports the bumping strains are removed from the bolts which hold the bumping block in position on the supports, thereby prolonging the life of the bumping post.

While I have described more or less precisely the details of construction of my invention I do not wish to be understood as limiting myself thereto as I contemplate changes in form and proportion of parts and the substitution of equivalents as circumstances may suggest or render expedient without departing from the spirit of my invention.

I claim:

1. A bumping post, comprising in combination, a cast metal hollow block having

a bumping face at one end, and supports therefor, said supports being formed of T-rails bent into substantially inverted U 45 shape in plan and elevation, and with the ends of said supports straight and bolted to the track rails along the insides thereof, said block being formed with recesses in its sides which conform to the cross-section of 50 the supports as well as to the centrally bent portion thereof; the block being mounted on said supports with the supports lying within the recesses in the block.

2. A bumping post comprising a block 55 and symmetrical supports therefor, said block being mounted on said supports by recesses formed in the sides of the block through which said supports pass in non-circular manner, said recesses and a portion 60 of the supports within the same being curved in side elevation in such a manner that shocks received by said blocks may be transmitted directly to said supports without displacement of said block thereon. 65

3. A bumping post comprising a block of cast metal and supports therefor, said block being mounted on said supports by recesses formed in the sides of the block, said recesses being curved in elevation in a non-circular path to correspond to the curvature 70 of said supports and shaped in section to correspond to the section of said supports, bolts passing through the supports and the block, said supports being arranged in such 75 a manner that blows against said block may be transmitted to said supports solely through the recessed engagement therewith, thereby relieving said bolts of shearing strain. 80

Signed at Chicago, Illinois, this 23rd day of February, 1922.

RICHARD D. GALLAGHER.
